(57) **CLAIM**

The ornamental design for a bottle, as shown and described.

DESCRIPTION

FIG. 1 is a top perspective view of my new design for a bottle, shown with environmental figurine within for clarity of disclosure;

FIG. 2 is another top perspective view thereof, shown with environmental radiating lines;

FIG. 3 is a front elevational view thereof;

FIG. 4 is a top perspective view of my new design for a bottle, shown with the environmental figurine removed;

FIG. 5 is a bottom perspective view thereof;

FIG. 6 is a front elevational view thereof;

FIG. 7 is a rear elevational view thereof;

FIG. 8 is a left side elevational view thereof;

FIG. 9 is a right side elevational view thereof;

FIG. 10 is a top plan view thereof; and

FIG. 11 is a bottom plan view thereof.

FIG. 12 is an enlarged view of a portion thereof as shown in FIG. 1.

FIG. 13 is an enlarged view of a portion thereof as shown in FIG. 2; and,

FIG. 14 is an enlarged view of a portion thereof as shown in FIG. 3.

The broken line showing of an environmental figurine in FIGS. 1-3 and 12-14 forms no part of the claimed design. The environmental radiating broken lines in FIGS. 2-3 and 13-14 depict a state of illumination and form no part of the claimed design.

1 Claim, 13 Drawing Sheets
